INVENTOR

BY Victor J. Evans

ATTORNEY

J. L. Wright

WITNESS:

UNITED STATES PATENT OFFICE

MAURICE ROBBINS, OF BOSTON, MASSACHUSETTS

NECKTIE

Application filed January 7, 1929. Serial No. 330,888.

This invention relates to a necktie, the general object of the invention being to place a core of pressure resisting substance, such as sponge rubber and inflated rubber tubing or woven or knitted fabric in the small end part of the tie so as to give the tie, when knotted, a much better appearance than an ordinary tie, the core also acting to facilitate the untying of the tie as well as to increase the life of the tie by preventing the knot being made too tight, which damages the fabric from which the tie is formed.

This invention also consists in certain other features of construction and in the combination and arrangement of the several parts, to be hereinafter fully described, illustrated in the accompanying drawing and specifically pointed out in the appended

20 claim.

In describing the invention in detail, reference will be had to the accompanying drawing wherein like characters denote like or corresponding parts throughout the several views, and in which:

Figure 1 is a perspective view of the improved tie.

Figure 2 is a view of the core.

Figure 3 is a section on line 3—3 of Figure 2.

Figure 4 is a section on line 4—4 of Figure 2.

Figure 5 is a transverse sectional view through a modified form of core.

Figure 6 is a similar view through another form of core.

As shown in these views, I form a core 1 of sponge rubber or woven or knitted fabric, or the core may be formed of an inflated rubber tubing or cotton batting, etc. This core may be of circular cross sectional shape, as shown in Figures 2, 3, and 4, or it may be of oval shape, as shown at 1' in Figure 5, or it may be of rectangular shape, as shown at 1" in Figure 6. The inner end of the core is of wedge shape, as shown at 2, and its outer end is preferably rounded, as shown at 3. This core is placed in the small end part 4 of the necktie A, so that it will keep this small end portion expanded

and thus when the necktie is knotted, the core will act to fill out the knot and give it a much better appearance than an ordinary necktie. It also facilitates the untying of the knot, as the yieldable nature of the core prevents the knot being made too tight so that the knot can be easily untied or the knotted portion can be slipped over the part containing the core without untying the knot. In this latter case, the wedge end 2 facilitates the passing of the knotted part upon the core part.

The invention also acts to increase the life of the tie by preventing the knot being made too tight, which acts to damage the fabric from which the tie is formed. The part A' of the necktie between the large and small ends thereof may be stitched, as shown at 5, to stiffen this part.

It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:

A necktie of the class described comprising the usual neck encircling portion and the inner and outer flap portions, the inner flap portion being of tubular form, and a core of yieldable material fitted within said inner flap portion and having its inner end tapered at its opposite sides in the direction of the neck encircling portion of the tie, the outer end of the core being semi-spherical.

In testimony whereof I affix my signature.

MAURICE ROBBINS.
